(57) **CLAIM**

The ornamental design for a launch head for a net launching device, as shown and described.

DESCRIPTION

FIG. 1 is a bottom perspective view of the first embodiment of a launch head for a net launching device, showing our new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view of the second embodiment of a launch head for a net launching device, showing our new design;

FIG. 9 is a front side elevation view thereof;

FIG. 10 is a rear side elevation view thereof;

FIG. 11 is a left side elevation view thereof;

FIG. 12 is a right side elevation view thereof;

FIG. 13 is a bottom perspective view of the second embodiment of a launch head for a net launching device, showing our new design;

FIG. 14 is a front side elevation view thereof;

FIG. 15 is a rear side elevation view thereof;

FIG. 16 is a left side elevation view thereof; and,

FIG. 17 is a right side elevation view thereof.

The broken line in the drawings depicts unclaimed portion of the launch head only and forms no part of the claimed design.
